HOT BEVERAGE MERCHANTISER

Eugene Buday, Wilkins Township, Allegheny County, Pa.
(324 Sunset Drive, Pittsburgh, Pa. 15235), and Sol
Blackman, 1152 Towanda Terrace, Cincinnati, Ohio
45216

Filed Dec. 6, 1974, Ser. No. 530,440

Term of patent 7 years

Int. Cl. D6—04; D20—02

U.S. Cl. D6—168

FIG. 1

FIG. 2

FIG. 3

FIG. 6

FIG. 5

FIG. 4

FIG. 1 is an enlarged perspective view of a hot beverage merchandiser showing our new design;

FIG. 2 is a top plan view thereof;

FIG. 3 is a bottom plan view thereof;

FIG. 4 is a front elevational view thereof;

FIG. 5 is a side elevational view thereof, the opposite side being identical;

FIG. 6 is a rear elevational view thereof.

We claim:

The ornamental design for a hot beverage merchandiser, as shown and described.
